UNITED STATES PATENT OFFICE.

VALENTIN JAKOB ODHNER, OF HINDAS, SWEDEN.

CALCULATING WHEEL OF CALCULATING MACHINES.

Application filed May 11, 1920. Serial No. 380,472.

To all whom it may concern:

Be it known that I, VALENTIN JAKOB ODHNER, a subject of the King of Sweden, and resident of Turisthotellet, Hindas, in the Kingdom of Sweden, have invented certain new and useful Improvements in Calculating Wheels of Calculating Machines, of which the following is a specification, reference being had therein to the accompanying drawings.

In calculating machines of the type disclosed in the U. S. patent to W. T. Odhner 514,725, February 13, 1894, the tens-pins, hundreds-pins, etc., of the calculating wheels are swingable laterally or transversely of the wheels, owing to which fact the thickness of the wheels or the distance between the wheels must be sufficient for the purpose. Differing from the said arrangement the said pins according to this invention are swingable or movable in the plane proper of the said wheel. Owing to the said arrangement the wheels may be thinner or the distance between the wheels may be reduced. As the machines have a great number of calculating wheels the length of the machine can be considerably reduced by the said arrangement. In connection with the shifting of the pin the present invention also relates to means for shifting the part stated in the U. S. Letters Patent No. 1,348,576, granted August 3, 1920, which closes and opens respectively the opening, provided in the calculating wheel through which the star wheel, adapted to lock the registering wheel, passes, while the 10-pin, etc., is in operative position.

The accompanying drawings show some forms of execution of the invention. Figs. 1 and 3 show in a side view one form of execution with the 10-pin, etc., in inoperative and operative position respectively. Fig. 2 is a cross section of the parts having the same position as shown in Fig. 3. Figs. 4 and 5, Figs. 6 and 7 and Figs. 8 and 9 show in side views three further forms of execution with the said pin, etc., in inoperative and operative position respectively. Figs. 10 and 11 show in two different positions means for closing and opening respectively the passage provided in the calculating wheel for the star-wheel used in combination

with the device shown in Figs. 1 to 3 inclusive. Figs. 12 and 13 show in the same manner means for closing and opening the said passage used in combination with the device shown in Figs. 6 and 7. Figs. 14 and 15 show in the same manner means for opening and closing the said passage used in combination with the device shown in Figs. 8 and 9. Figs. 16 and 17 are sections of a calculating machine showing two positions of the device illustrated in Figs. 10 and 11.

In a recess provided in the calculating wheel 1, Figs. 1 to 3 inclusive, a two-armed part is pivoted at 2, the one arm 3 of which forms the 10-pin, etc., and the other arm 4 of which serves to move the said pin into operative position. The said arms 3 and 4 are located in different planes parallel to the calculating wheel, Fig. 2. As shown in the drawings the arms 3 and 4 are swingable in the plane of the calculating wheel 1. For the said reason the calculating wheels may be thinner than in machines provided with 10-pins, etc., swingable transversely of the calculating wheels, which results in a reducing of the length of the machine. The said arms are normally held in the position shown in Fig. 1 by a leaf spring 5. 6 is the tens-transmitting part. The said part 6 may be shifted in ordinary manner but is so arranged, that the same, moved to its operative position, Fig. 3, swings the arm 4 inwards towards the calculating wheel 1 and moves the arm or 10-pin 3 from its inoperative position, Fig. 1, to its operative position, Figs. 2 and 3, in which it extends outside the periphery of the wheel 1.

In Figs. 4 and 5 the 10-pin 3 is movable longitudinally in the calculating wheel 1 and is held by a spring 5 in its inner position, Fig. 4. The said pin 3 is provided with teeth meshing with teeth provided on an arm 7, which is pivoted to the calculating wheel 1 and normally extends outside the wheel 1. When the tens-transmitting part 6 is in its operative position, Fig. 5, it swings the arm 7 inwards, during which operation the arm 7 moves the pin 3 outwards into its operative position by means of the described gearing.

In the form of execution shown in Figs.

6 and 7 the 10-pin 3 as well as the part 8, located parallelly to the said pin and adapted to shift the same, is movable longitudinally in the calculating wheel 1. The pin 3 and the part 8 are connected with a two-armed lever 9, pivoted to the calculating wheel, by means of a pin- and slot-connection, so that, as the part 8 is moved inwards by the tens-transmitting part 6 against the action of a spring 10, the pin 3 is moved outwards, as shown in Fig. 7.

In Figs. 8 and 9 the pin 3 is movable longitudinally in the calculating wheel 1 and is provided with a lateral pin 11, which engages a curved slot 12 provided in a movable plate 13. The said plate 13 is movable peripherally on the wheel 1 and is guided by curve shaped slots 14, engaged by pins 15 fixed in the wheel 1 and provided with heads. A two-armed lever 17 is pivoted at 16 to the wheel 1 and is connected by a pin- and slot-connection 18 with the plate 13, so that by the swinging of the lever 17, effected by the transmitting part 6, the plate 13 is moved towards the right, Fig. 9, and by means of the curve slot 12 moves the pin 3 into its operative position. A spring 5 returns the parts to the position shown in Fig. 8.

19, Figs. 10 and 11, designates the star-wheel, described in the Letters Patent mentioned above and bearing against the periphery of the calculating wheel for locking the registering wheel in adjusted position. 20 is the ordinary transmitting wheel, which is engaged by the pins of the calculating wheel, brought into operative position, for shifting the registering wheel. In order that the star-wheel may be able to rotate for a distance of one tooth, while the 10-pin, etc., actuates the wheel 20, an opening 21 is provided in the periphery of the calculating wheel 1 at the position of the pin 3. At the said opening 3 a plate 23, which is pivoted 45 at 22 to the calculating wheel 1, normally is located and bears against the star-wheel 19 and locks the same, while the pin 3 in inoperative position passes the star-wheel. As the pin 3 is brought into operative position 50 in the manner stated above with reference to Figs. 1 to 3 inclusive, the plate 23 is moved to the position shown in Fig. 11, so that the opening 21 is free and the star-wheel can pass through the same. The said 55 moving of the plate 23 is effected by a pin 24 provided on the arm 4 and engaging a slot 25 in the plate 23. As the pin 3 is returned to its inoperative position, the plate 23 is returned to the position shown in Fig. 60 10.

In the arrangement shown in Figs. 12 and 13 the movable part 8 (compare Figs. 6 and 7) is connected by means of a pin 26 with a plate 28 movable in a guide 27 provided on 65 the calculating wheel 1. The said plate 28

normally covers the opening 21 in the periphery of the wheel 1 but is moved to the position shown in Fig. 13 by the described means, as the pin 3 is moved outwards to its operative position.

In Figs. 14 and 15 the plate 13 (Figs. 8 and 9) has a projection 29, which normally covers the opening 21 of the wheel 1 but is moved, during the movement of the plate 13 for bringing the pin 3 into operative position, into a position lateral of the opening 21, as shown in Fig. 15, so that the star-wheel can pass.

In Figure 16, the member 6 pivoted to the slide is shown occupying an inactive position, that is, the arm 4 is not acted upon by the member 6 and consequently the 10-pin rests in the inactive position shown as it passes the member 6 incident to the rotation of the calculating wheel in the direction indicated by the arrow. The arm 6 is retained in this position by the displaceable and spring actuated pin 30 which latter rests against one side of the shaft 31. During the continued operation of the machine, the digit pins located in another calculating wheel (not shown) of the nearest inferior value pass the toothed wheel 20 whereby the digit pins which have been brought into operative position advance said toothed wheel 25 and the registering wheel 32 so that the same are moved into the positions shown in Figure 17. The above mentioned calculating wheel carrying the digit pins, though not shown in the accompanying drawing, is fully disclosed in Patent 514,725 above referred to.

The pin 33 passes the member 6 and shifts it to the position shown in Fig. 17, the pin 30 being displaced by the shaft 31 so as to yieldingly lock the member 6 in the new 105 position, the pin 30 bearing against the opposite side of the shaft 31. As the member 6 and the arm 4 are located in the same plane, the latter will be shifted by the member 6 pressed closely to the edge of the calculating wheel, the pin 3 being advanced into operative position so that, upon continued rotation of the wheel 1, it meshes with the toothed wheel 20 and advances it one step. It will be understood that the pin 110 3 and the toothed wheel 20 are located in the same plane. At the same time that the pin 3 is shifted to operative position, the plate 23 is moved aside so that a tooth of the star-wheel 19 located in the same plane as the plate may freely pass through the opening 21 whereby said star wheel and the toothed wheel 20 and the registering wheel may be advanced. The 10-pin is then moved back into inoperative position by the spring 125 5. From the foregoing it will be understood that the three groups of parts 6 and 4, 3 and 20, 19 and 23 are located in three different planes, that is to say, the member 6 and the arm 4 are located in one plane, the 130

10-pin and the toothed wheel 20 in another plane, and the star wheel 19 and the plate 23 in another plane.

Having now described my invention, what I claim as new and desire to secure by Letters Patent is:

1. In a calculating machine, a calculating wheel, a pin carried by and movable in the plane of the calculating wheel, a shiftable transmitting part, a part movable in the plane of the calculating wheel and adapted to be actuated by the said transmitting part and brought into operative position, and means connecting the said pin and the said movable part, whereby the pin is brought into operative position as the said movable part is actuated by the transmitting part.
2. In a calculating machine, a calculating wheel, a pin swingable in the plane of the calculating wheel, a shiftable transmitting part, and an arm connected with the said pin and swingable in the plane of the calculating wheel and adapted to be actuated by the said transmitting part and brought into operative position whereby the said pin is brought into operative position, as the said arm is actuated by the transmitting part.
3. In a calculating machine, a calculating wheel, a pin movable in the plane of the calculating wheel, a shiftable transmitting part, a part movable in the plane of the calculating wheel and adapted to be actuated by the said transmitting part and brought into operative position, means connecting the said pin and the said movable part, so that the pin is brought into operative position as the said movable part is actuated by the transmitting part, said calculating wheel having a peripheral opening therein, a movable part normally covering the said opening, a star-wheel bearing against the calculating wheel and locking the registering wheel of the machine, and means connecting the said part, movable in the plane of the calculating wheel, with the said covering part in such manner whereby when the pin is brought into operative position, the covering part is brought into inoperative position and permits the star-wheel to pass through the said opening one tooth at a time.
4. In a calculating machine, a calculating wheel, a pin swingable in the plane of the calculating wheel, a shiftable transmitting part, an arm connected with the said pin and swingable in the plane of the calculating wheel and adapted to be actuated by the said transmitting part and brought into operative position whereby the said pin is brought into operative position as the said arm is actuated by the transmitting part, said calculating wheel having a peripheral opening therein, a movable part normally covering the said opening, a star-wheel bearing against the calculating wheel and locking the registering wheel of the calculating machine, and means connecting the said swingable arm with the said swingable part in such manner, that, when the pin is brought into operative position, the covering part is brought into inoperative position and permits the star-wheel to pass through the said opening one tooth at a time.

In witness whereof, I have hereunto signed my name.

VALENTIN JAKOB ODHNER.
